HEDDLE FRAME FOR LOOMS

John Jacob Kaufmann, Elkins Park, Pa., assignor to Steel Heddle Manufacturing Company, Philadelphia, Pa., a corporation of Pennsylvania.

Application April 1, 1936, Serial No. 71,996

6 Claims. (Cl. 139—92)

This invention relates to heddle frames for looms, and it relates more particularly to certain improvements in the devices used in such frames for supporting the heddle bars intermediate their ends.

The principal object of the present invention is to provide an improved form of device for supporting the heddle bars of loom harness frames intermediate their ends.

10 A further object of the invention is to provide a heddle bar supporting device for loom harness frames which will be simple, durable, and efficient and which may be easily and conveniently manipulated by the loom operator to permit the 15 heddle bar to be inserted in and removed from the device.

15 A further object of the invention is to provide a device of the character aforesaid in which the heddle supporting bar will be securely held against accidental disengagement, and in the use of which wear of the supporting device and of the heddle supporting bar at the point of support will be reduced to a minimum.

20 The nature and characteristic features of the 25 present invention will be more readily understood from the following description taken in connection with the accompanying drawing forming part hereof, in which:

Figure 1 is an elevational view of a heddle frame 30 provided with heddle bar supporting devices embodying the main features of the present invention;

Fig. 2 is a fragmentary detail thereof enlarged; Fig. 3 is a vertical section taken approximately 35 on the line 3—3 of Fig. 2;

Fig. 4 is a horizontal section, still further enlarged, taken on the line 4—4 of Fig. 3;

Fig. 5 is a side elevation of a bolt member constituting one of the principal elements of the 40 device, the other parts being removed therefrom;

Fig. 6 is a perspective view of a slideable locking sleeve, detached, constituting another of the elements of the device;

Fig. 7 is a view similar to Fig. 2 illustrating a modified form of the invention, the same being provided with positive locking means; and

Fig. 8 is a vertical section taken approximately on the line 8—8 of Fig. 7.

50 Referring to the drawing, the heddle frame there shown comprises top and bottom rails 10, usually made of wood, and connected at their ends by means of the metallic side strips 11. Extending from end to end of the heddle frame and arranged near the top and bottom rails 10 are the

supporting bars 12 on which the heddles 13 are mounted in the ordinary manner.

The devices comprising the present invention are mounted at suitable portions of the top and bottom rails 10, extending inwardly therefrom. Each of these devices includes a bolt member 20 having a shank 21, the end of which may be threaded as at 22 in a manner similar to that of an ordinary wood screw for mounting the same in the rail, although it will be readily understood that the devices may be secured to the rails in any other preferred manner.

10 The bolt member 20 is also provided with a head portion 23 having flat sides, the portion adjacent the shank of the bolt member being substantially rectangular in cross section, and slidably mounted thereon is a complementally formed sleeve member 30 preferably made from sheet metal punched and formed to the proper shape.

15 The shank portion of the bolt member is provided with struck-up lugs 24 to provide shoulders against which one end of the coil spring 25 bears. The other end of the coil spring bears against the sleeve member 30 which is mounted on the head portion 23 of the bolt member, the spring impelling this sleeve member 30 toward the end of the head portion 23 of the bolt member.

20 The head portion 23 of the bolt member is also provided with a widened portion 26, thus providing a shoulder 27 which serves as a limit for 25 the movement of the sleeve member, preventing the same from being impelled too far toward the end of the head portion 23 of the bolt member. The portion of the sleeve member 30 which extends around the narrow part of the head portion 35 23 of the bolt member is so formed as to make a snug sliding fit with respect thereto.

30 The widened part 26 of the head portion 23 of the bolt member is also provided with a recess 28 for the reception of the heddle supporting bar 40 12. The sleeve member 30 is also provided with parallel extensions 31 disposed on each side of the head portion 23 of the bolt member and each provided with a recess 32 adapted to engage one edge of the heddle supporting bar 12 when the 45 sleeve member 30 is in the normal operative position to hold the heddle supporting bar 12 within the recess 28 in the head portion 23 of the bolt member.

40 The sleeve member 30 is also provided, at the 50 end against which the coil spring 25 abuts, with sidewise extending ears 33, one of these being provided on each side of said sleeve member 30.

55 In the use of the device, whenever it is desired to insert or remove the heddle supporting bar 12, 55

the ears 33 of the sleeve member 30 are engaged by the fingers of the operator and the sleeve member 30 thereby withdrawn, so that the ends of the recessed extensions 31 are brought to a 5 position to free the recess 28 in the head portion 23 of the bolt member; whereupon the heddle supporting bar 12 may be freely inserted or removed, as the case may be. When the heddle supporting bar 12 is in its proper position within 10 the recess 28 of the head portion 23 of the bolt member and the sleeve member 30 is released by the operator, the recessed extensions 31 of said sleeve member 30 will engage the heddle bar on both sides of the head portion 23 of the bolt member, thus providing a lock on each side of said 15 head portion. The provision of the two ears 33 on each side of the sleeve member 30 enables the operator to control the same quite easily, it being noted that the pressures and forces exerted are 20 symmetrical at all times, so that said sleeve member 30 will be freely operable and will not tend to stick or jam.

In the form of the device shown in Figs. 7 and 8 of the drawing the struck-up lug portions 24 25 on the shank 21 of the bolt member are omitted, and in lieu thereof the shank portion 21 of the bolt member is provided with a machine screw thread 29 upon which a thumb nut 40 is complementally threaded. The thumb nut 40 is re- 30 cesses as at 41 for reception of the end of the coil spring 25, this recess being of sufficient extent so that when the thumb nut 40 is screwed down, the said coil spring 25 will be contained entirely within the same, and the rim of the thumb nut 35 40 will bear directly against a washer 42 which is interposed between the lower end of the spring 25 and the upper end of the sleeve member 30. In this manner the sleeve member 30 may be positively locked in position by means of the thumb nut 40 to the end that accidental disengagement of the heddle supporting bar 12 from the head portion 23 of the bolt member will be 40 prevented.

I claim:

1. In a heddle frame, the means for supporting 45 the heddle bars intermediate their ends, comprising a bolt member mounted in the heddle frame rail, said bolt member having a head portion provided with flattened sides and a recess in which the heddle supporting bar is positioned, the part of the head portion of said bolt member in which the recess is located being widened thereby to provide a shoulder, a sleeve member slidably mounted on said head portion limited in its movement toward the end of said head portion by said shoulder, and a spring for impelling said sleeve member to locking position, said sleeve member being made of a single piece of sheet metal shaped to provide a portion extending entirely around a part of the head portion of the bolt member and portions at one end engaging the heddle supporting bar to lock the same within the recess in the head portion of the bolt member.

2. In a heddle frame, the means for supporting 65 the heddle bars intermediate their ends, comprising a bolt member mounted in the heddle frame rail, said bolt member having a head portion provided with flattened sides and a recess in which the heddle supporting bar is positioned, the part of the head portion of said bolt member in which the recess is located being widened thereby to provide a shoulder, a sleeve member slidably mounted on said head portion, said sleeve member having a portion for contact with said shoul-

der to limit the movement of the sleeve toward the end of said head portion, and a spring for impelling said sleeve member to locking position, said sleeve member being made of a single piece of sheet metal shaped to provide a portion extending entirely around a part of the head portion of the bolt member and extensions at one end on each side of the head portion of the bolt member provided with recesses to engage the heddle supporting bar and lock the same within the recess in the head portion of the bolt member. 10

3. In a heddle frame, the means for supporting 15 the heddle bars intermediate their ends, comprising a bolt member mounted in the heddle frame rail, said bolt member having a head portion provided with flattened sides and a recess in which the heddle supporting bar is positioned, the part of the head portion of said bolt member in which the recess is located being widened thereby to provide a shoulder, a sleeve member slidably mounted on and extending entirely around said head portion, said sleeve member having a portion for contact with said shoulder to limit the movement of said sleeve toward the end of said head portion, and a spring for impelling said 20 sleeve member to locking position, said sleeve member having at one end thereof portions extending along said flattened sides and engaging the heddle supporting bar to lock the same within the recess in the head portion of the bolt member, said sleeve member also having symmetrical- 25 ly disposed ears at its other end extending outwardly on both sides thereof adapted to be engaged by the fingers of the operator to withdraw the sleeve member from the locking position. 30

4. In a heddle frame, the means for supporting 35 the heddle bars intermediate their ends, comprising a bolt member mounted in the heddle frame rail, said bolt member having a head portion provided with flattened sides and a recess in which the heddle supporting bar is positioned, the part of the head portion of said bolt member in which the recess is located being widened thereby to provide a shoulder, a sleeve member slidably mounted on and extending entirely around said head 40 portion limited in its movement toward the end of said head portion by said shoulder, and a spring having one end bearing against said sleeve member and tending to impel the same to locking position, said sleeve member having at one end 45 thereof portions extending along said flattened sides and engaging the heddle supporting bar to lock the same within the recess in the head portion of the bolt member, said sleeve member also having symmetri- 50 cally disposed ears extending outwardly on both sides thereof adapted to be engaged by the fingers of the operator to withdraw the sleeve member from the locking position. 55

5. In a heddle frame, the means for supporting 60 the heddle bars intermediate their ends, comprising a bolt member mounted in the heddle frame rail, said bolt member having a head portion provided with flattened sides and a recess in which the heddle supporting bar is positioned, the part 65 of the head portion of said bolt member in which the recess is located being widened thereby to provide a shoulder, a sleeve member slidably mounted on said head portion limited in its movement toward the end of said head portion by said shoulder, a spring having one end bearing against said sleeve member and tending to impel the same to locking position, said sleeve member being made of a single piece of sheet metal extending entirely around said head portion and 70

having extensions at one end on each side provided with recesses to engage the heddle supporting bar and lock the same within the recess in the head portion of the bolt member, said sleeve member also having symmetrically disposed ears at its other end extending outwardly on both sides thereof adapted to be engaged by the fingers of the operator to withdraw the sleeve member from the locking position.

6. In a heddle frame, the means for supporting the heddle bars intermediate their ends, comprising a bolt member mounted in the heddle frame rail, said bolt member having a head portion provided with flattened sides and a recess in which the heddle supporting bar is positioned the part of the head portion of said bolt member in which the recess is located being widened thereby to provide a shoulder, a sleeve member slidably mounted on said head portion limited in its move-

ment toward the end of said head portion by said shoulder, and a spring having one end bearing against said sleeve member and tending to impel the same to locking position, said sleeve member being made of a single piece of sheet metal shaped to provide a portion extending entirely around a part of the head portion of the bolt member and extensions at one end on each side of the head portion of the bolt member provided with recesses to engage the heddle supporting bar and lock the same within the recess in the head portion of the bolt member, said sleeve member also having symmetrically disposed ears at its other end extending outwardly on both sides thereof adapted to be engaged by the fingers of the operator to withdraw the sleeve member from the locking position. 5 10 15
